SUBMINIATURE COAXIAL CONNECTOR FITTING

Albert E. Powell, Old Greenwich, Conn., assignor to
Micon Electronics, Inc., Garden City, Long Island,
N.Y.

Filed Sept. 26, 1962, Ser. No. 71,857

Term of patent 14 years

(Cl. D26—1)

FIG. 1 is a side elevation of a subminiature coaxial connector fitting with cooperating components, shown in phantom for illustrative purposes only.

FIG. 2 is a front elevation as viewed from the left of FIG. 1;

FIG. 3 is a rear elevation as viewed from the right of FIG. 1;

FIG. 4 is a plan view as viewed from the top of FIG. 1; and

FIG. 5 is a bottom view as viewed from below FIG. 1.

I claim:

The ornamental design for a subminiature coaxial connector fitting, substantially as shown and described.
